BICYCLE FRAME

Charles F. Voytech, 208 S. LaSalle St.,
Chicago, Ill. 60604

Filed July 28, 1966, Ser. No. 3,242

Term of patent 14 years

(Cl. D90—8)

FIG. 1 is a side elevational view of the bicycle frame;
FIG. 2 is a plan view of the bicycle frame of FIG. 1;
FIG. 3 is a bottom view of the bicycle frame of FIG. 1;
FIG. 4 is a rear elevational view of the bicycle frame of FIG. 1 looking toward the left in FIG. 1; and

FIG. 5 is a front elevational view of the bicycle frame of FIG. 1 looking toward the right in FIG. 1.

The broken lines on FIGS. 1-5 are disclosed for illustration purposes only to show how the frame is used in a bicycle.

In view of the prior art, the characteristic features of my design reside in the overall appearance resultant from the arcuate continuation of the lower rear frame element through the crank pedal area up to and through the upper frame member terminating in the saddle post, taken with

the appearance resultant from the elimination of a conventional expected front down tube element, both consonant with the curvilinear theme, as shown.

I claim:

The ornamental design for a bicycle frame, substantially as shown and described.
